CLAIM

We claim the ornamental design for a remote control for a surgical system, substantially as shown and described.

DESCRIPTION

FIG. 1 is a top view of a remote control for a surgical system showing our new design;
FIG. 2 is a perspective bottom view thereof;
FIG. 3 is a side view thereof; and,
FIG. 4 is a perspective top view thereof.
FIGS. 1, 2 and 4 show features of a remote with broken lines. These features are for illustrating reference or environmental structure only and do not form any part of the claimed design.
